UNITED STATES PATENT OFFICE.

HENRY JACQUES GAISMAN, OF NEW YORK, N. Y.

WAIST-BELT.

SPECIFICATION forming part of Letters Patent No. 734,167, dated July 21, 1903.

Application filed October 8, 1901. Serial No. 77,951. (No model.)

To all whom it may concern:

Be it known that I, HENRY JACQUES GAISMAN, a citizen of the United States, and a resident of New York city, borough of Manhattan, State of New York, have invented certain new and useful Improvements in Waist-Belts, of which the following is a specification.

Some styles of belts are made by braiding strands of leather or other fabric into a substantially flat braid and providing fastening means at the ends for holding the belt around a waist; but in this class of belts there is an inherent disadvantage in that the braided strands permit the belts to stretch when strain is put upon the same; and it is the object of my invention to provide a belt of the class described with means to prevent such stretching. To this end I provide a braided belt with a non-elastic strip, cord, or strand which extends lengthwise of the belt and is secured thereto near opposite ends of the braid, whereby the belt is kept from stretching. As a means for retaining the strip, cord, or strand in proper position relatively to the braided strands I weave said strip or cord in with a plurality of the strands, so that said cord will be retained in its proper position.

Reference is to be had to the accompanying drawings, forming part hereof, wherein— Figure 1 is a face view of the inner side of a belt embodying my invention, and Fig. 2 is an enlarged detail view of part thereof. In the drawings the numeral 1 indicates the main body portion of the belt, which is composed of a plurality of strands 1^a, braided together in well-known manner, preferably forming a flat braid, any suitable number of such strands being used. At one end of the body portion is a tongue or the like 2, which may be formed integral with the strands 1^a by slitting a piece of leather or fabric from

the point 2^a and braiding such strands, or the strands may be separate from the tongue and secured thereto in well-known manner. At 45 the opposite end of the body portion of the belt is secured a fastener or buckle 3, adapted to engage the tongue 2, and said buckle may be attached to the strands 1^a in well-known manner. I have shown the buckle as 50 attached to a web 4, that is secured to the strand 1^a, as by threads 4^a.

5 is a non-elastic strip, cord, or strand extending longitudinally of the braided portion of the belt and having its ends firmly attached 55 to the belt, as by being tied to a strand 1^a or by being held by a rivet or stitches, as at 1^x, or in other suitable manner. Means are provided to maintain the strip, cord, or strand 5 in line with the body portion of the belt, so 60 that it will not sag below the belt when in use, and for this purpose I have shown the strip or cord 5 as passing behind certain of the strands 1^a, as at 1^b, thereby being retained between the strands, as shown; but other 65 means may be provided for maintaining the strip or cord 5 in line with the body portion of the belt between the ends of the cord, if preferred.

Having now described my invention, what 70 I claim is—

A belt comprising braided strands, means for attaching the ends of the belt together, and a strip or cord extending longitudinally along the inner face of the braided strands 75 and firmly attached near its ends to the belt, said strip or cord being retained in position on the belt by strands of the belt which pass on opposite sides of the strip or cord, substantially as described.

HENRY JACQUES GAISMAN.
